CONTAINER CAPPING MACHINE

Richard D. Anderson, Baton Rouge, La., assignor
to Standard Oil Development Company, a corporation of Delaware

Application December 30, 1933, Serial No. 704,772

8 Claims. (Cl. 113—1)

This invention relates to improvements in apparatus for capping receptacles.

It is an object of this invention to mechanically dispose a grease plunger and cap upon a filled container. It is a further object of this invention to provide for the positive separation and placing of a grease plunger and container cap respectively into position upon the container.

Other objects will be apparent from the specification and from the accompanying drawings in which latter—

Fig. 1 is a side elevational view of the device; Fig. 2 is a front elevational view of the device;

Fig. 3 is a top plan view of the device;

Fig. 4 is a rear elevational view of the device;

Fig. 5 is a transverse sectional view taken along the line V—V of Fig. 3 and showing the barrel pistons in elevated position;

Fig. 6 is a side elevational view of the structure illustrated in Fig. 5;

Fig. 7 is a top plan view of the placing spider taken along the line VII—VII of Fig. 5;

Fig. 8 is a top plan view along the line VIII—VIII of the structure illustrated in Fig. 6 showing the capping head;

Fig. 9 is a rear detail view of the capping head column and spider;

Fig. 10 is a top plan view taken along the line X—X of Fig. 1 showing the driving mechanism;

Fig. 11 is a diagrammatic view of the mechanism for actuating the spider;

Fig. 12 is a diagrammatic view of the mechanism for effecting the plunger movement;

Fig. 13 is a diagrammatic view of the mechanism for effecting movement of the capping head;

Figs. 14 to 19, inclusive, are diagrammatic views showing the position of the apparatus for placing the grease plunger and can top into the containers at different stages of their movement.

Fig. 20 is a longitudinal sectional view taken along the lines XX—XX of Fig. 3 showing a barrel piston in lowered position; and

Fig. 21 is a transverse sectional view taken along the line XXI—XXI of Fig. 20.

Referring particularly to Figs. 3 and 7 of the drawings, reference character A designates containers or cans which are fed from a guideway B into position to be engaged by a placing spider C. The placing spider C is driven in a counter-clockwise direction as viewed in Figs. 3 and 7 in regular strokes, the intermission being longer than the moving time of the strokes. Each container A is positioned by the placing spider first at location X directly under a grease plunger

positioning device D, see Fig. 3, where a grease plunger a is fitted into the container of grease. The grease plunger a facilitates the filling of the grease gun during subsequent use of the grease by a consumer. The container A with its grease plunger a is next delivered to an inspection place Y during one stroke of the placing spider, and is then delivered to a position z directly under mechanism F for positioning a container cap b upon the container. The container is then delivered by the placing spider to a discharge guideway G.

The framework of the apparatus includes a table 1 which is supported by legs 2 from a base 3. A center column 4 is carried by the base 3 and extends upwardly through the table 1.

Placing spider

The placing spider C positions and feeds the containers A through the apparatus from the guideway B having a trough 5 across the table top 1 to the discharge guideway G. A transfer rail 6 guides the container A into the path of the placing spider C. The placing spider C is moved in rotation around the column 4 as an axis in a counter-clockwise direction as viewed in Fig. 3 by mechanism to be later described. The movement of the spider C is in regular strokes with the intermission between strokes consuming a longer period of time than does the moving time of the spider. The spider C is provided in the preferred embodiment with eight prongs 9 which protrude outwardly from a collar or hub 10. The prongs 9 of the spider are disposed in spaced relation to the table 1. The collar 10 of the spider encircles the column 4 and rests upon the capping table 1. The hub or collar 10 is provided within its inner periphery with a notched ratchet ring 20.

The spider is driven in rotation through the following arrangement of parts. The eight point notched ratchet ring 20 is engaged by a ratchet pawl 23 which protrudes through a slot 25 in the central column 4. The ratchet pawl 23 is mounted in a head 28 on the top end of a shaft 29 within the column 4. The ratchet pawl is driven in rotary reciprocating movement from a motor 32 as follows: See Figs. 10 and 11. The drive shaft of the motor 32 is geared to a worm 33 through gears 34 and 35 and worm shaft 36. The worm 33 drives a worm gear 37 and a shaft 38. The shaft 38 through bevel gears 39 and 40, actuates the main drive shaft 41 of the machine. Crankdisc 42 fixed to shaft 41 actuates a cross-head 43 in reciprocating movement in a guide

44 by means of a connecting rod 45. The cross-head 43 engages an arm 47 which latter is fulcrumed and supported at 48. The arm 47 actuates an arm 50 which latter is keyed to the 5 shaft 29. The pawl 23 is therefore driven in rotary reciprocating movement about the shaft 29 as an axis. The pawl 23 moves the spider C in counter-clockwise rotation as viewed in Fig. 7 for one eighth of a revolution due to engagement of 10 the pawl 23 with one of the slots of ratchet 20. Upon reversing the stroke of the pawl 23, the end of the pawl slides freely upon the inclined surface of the ratchet slot until it engages the base of the next adjoining slot. The pawl is 15 forced radially outwardly from the head 28 by means of a helical spring 52. A spring stop 55 see Fig. 7 holds the spider in fixed position while the ratchet pawl 23 is making its return or clockwise movement.

20

Capping head

A capping head is provided for positively feeding a grease plunger *a* upon the containers in the position *x* and for positively feeding a container top *b* upon the containers while in a position *z*. The capping head comprises a tubular frame 65, see Figs. 6, 8 which embraces and is mounted for reciprocation upon the center column 4. The tubular frame 65 is provided with radially extending arms 66 which carry the barrels 67 and 68, respectively. The capping head barrel 67 is adapted to be loaded with a grease plunger *a* while in its elevated position. The capping head barrel 68 is adapted to be fed with a container top *b* while in its elevated position. The capping head barrels are then lowered into position, see Figs. 20 and 21, to deliver the grease plunger and container top, respectively, upon the containers A. The barrels are guided by the center column 30 4 and key 125 to be later described.

Plunger and container top magazines

Plungers *a* are fed into the plunger barrel 67 from a magazine 72, see Figs. 3, 14 to 20, inclusive. 45 Container tops *b* are fed into the capping head barrel 68 from a magazine 75. The magazines 72 and 75 are supported in an inclined position by means of frame pieces 76, which in turn are supported by the table 1. The magazines 72 and 50 75 are provided with discharge outlets which open into inlet openings 77 and 78 in the barrels 67 and 68 respectively, see Figs. 5 and 6. The delivery ends of the magazines 72 and 75 are semi-circular in shape as shown in Figures 3, 15, 17 55 and 19 and furnish a rest or slide for the grease plunger or can tops for the longest possible time. The plungers *a* and container tops *b* are fed from the magazines 72 and 75, respectively, positively through the inlet openings 77 and 78 into 60 the barrels 67 and 68 through the following arrangement of parts. The spider prongs 9 during each stage of rotation of the spider engage a pawl 80, see Figs. 1, 3 and 7, and move the pawl 80 in partial rotation. The pawl 80 is non-rotatably carried by a shaft 81, which in turn is supported by a suitable frame 82 carried by the table 1. The shaft 81 carries a crank 83 to which is attached a chain 84, which passes around a wheel 85. The wheel 85 is rotatably mounted in 65 a frame 86, extending from the under surface of the table 1. The chain 84 is attached to an arm 87 which is non-rotatably mounted upon a shaft 88. The shaft 88 is non-rotatably connected to a link 89. The link 89 is pivotally connected to 70 a link 90 which in turn is pivotally connected to

an arm 91, which carries fingers 92. Similarly, the link 89 is pivotally connected through a link 93 to an arm 94, which in turn carries a plurality of fingers 95.

The engagement of the arm 9 of the spider 5 against the pawl 80 forces the fingers 92 and 95 downwardly through a slot 100 in each magazine, to engage behind the grease plunger and the container top in the magazine and deliver them to their correct position in the barrels 67 10 and 68 respectively. Ninety per cent of the grease plungers and container tops slide in the barrels by gravity, but the finger action is positive. The grease plungers *a* and container tops *b* tend to slide by gravity into the capping head 15 barrels 67 and 68, respectively. Only one plunger or one top may slide into the barrels, the others being held back by triggers 104, see Fig. 20.

Capping head mechanism

20

The capping head barrels 67 and 68, respectively, are each provided with a pair of slides 105, see Figs. 5, 21, which are mounted for reciprocating horizontal movement through slots in the side walls of the barrels into position to close the barrels below the openings 77 and 78. The slides 105 are pivotally connected to bell cranks 106 and 107 which are pivotally supported at 108 to bracket 108a. The other arm of each bell crank is provided with a cam roll 110 for a purpose to be later described. When the capping head barrels are in their elevated position the slides 105 extend into the barrels to form a supporting surface for the bottom cap and plunger 35 which slide into the barrels. Only one plunger or one container cap or top can slide into each barrel, the others being held back by the trigger 104. Each trigger 104 is provided with a head 112 which protrudes through a slot in the bottom 40 of the magazine, into position to engage the bottom plunger or container top respectively. Each trigger 104 is pivotally supported at 114 upon the frame 157 of the machine, a helical spring 115 normally functioning to maintain the head of the trigger projecting into the magazine. 45

The placing fingers 92 and 95 are mounted on the magazines 72 and 75. The arms 91 and 93 work through two guides, one fastened on each side of the magazines. The guides are provided with the offset slots 100 so that when the fingers are pulled downward they are forced down into the bottom of the magazines 72 and 75. When the fingers are at the bottom end of their travel, the ends of the fingers are extending slightly past the inside of the barrels 67 and 68 of the capping head. At this point the fingers go out of control of the spacing spider and a spring 117 secured to the magazine and link 89 snaps the fingers into their elevated position. While each finger arm is coming back to its starting and resting position the offset slot 100 in the guides forces the fingers up out of the magazines 72 and 75. The placing fingers come in contact with only one plunger and one top. The placing fingers place the plunger or top correctly in the barrels of the capping head, should they not slide to the proper place of their own weight.

Capping head operation

70

The capping head barrels 67 and 68 carrying a plunger *a* and a container top *b* respectively are lowered from the position shown in Fig. 1 to the position shown in Figs. 20 and 21, in which the barrels are telescoped over the containers. 75

The capping head 65 is held in correct angular position to engage the cans by means of a vertically disposed key 125, see Fig. 20, in the center column 4. The lower portion of the barrels 67 and 68 are tapered internally as indicated at 126 in Figs. 14-16 and 18. Consequently, when the barrels descend upon containers which are not perfectly cylindrical, the barrels shape the containers to a perfect cylindrical shape and thereby insure the correct fitting of the plungers and tops.

The capping head is operated in vertical reciprocating movement through the following arrangement of parts, see Fig. 13. The main drive shaft 41 carries non-rotatably a cam 127 which is engaged by a cam follower 128 on a lever 129. The opposite end of the lever is pivotally supported at 131 from a support 132 depending from the table 1. A lift rod 134 is connected to an intermediate portion of the lever 129, and to an intermediate portion of a lever 136. The lever 136 is pivotally supported at one end by a bracket 137 projecting upwardly from the table 1. The lever 136 is pivotally connected 25 at 139 to the capping head 65.

At the time the placing fingers 92 and 95 are snapped back into their withdrawn position, the cam 127 is withdrawn from the cam follower 128, permitting the capping head to descend 30 by its own weight into the position illustrated in Figs. 20 and 21. This movement lowers the barrel slots 71 and 78 with respect to the delivery openings of the magazines, which are closed by the outer surface of the barrel walls:

As the barrels 67 and 68 descend, the grease plungers and container tops are permitted to slide downwardly in the magazines, as follows: The barrels 67 and 68 each carry an arm 144, see Figs. 1 and 20, to each of which is secured 35 a hook-shaped member 145. When the barrels descend, the hook-shaped members 145 engage a pin 146 upon the triggers 104 and pull the ends of the triggers downwardly out of the way of the plungers and tops in the magazines. Consequently, all of these plungers and container tops 40 in the magazines slide down, with the bottom plunger and top coming to rest against the outside wall of the barrels 67 and 68 respectively.

Positioning pistons

Pistons are provided to positively position the grease plunger and top upon the container. Each piston comprises a piston head 150, see Figs. 5, 6, 20 and 21, which is disposed within the barrels 67 and 68. Each piston head is suspended by means of a piston rod 151 and link 152. Each link 152 is provided with spaced rolls 153 forming a slot through which passes a lever 154. The lower roll 153 is mounted on a carriage 60 155 inside the piston 151. A spring 155a is located under this carriage with a tension greater than is necessary to put a top on a can, but not enough to crush the can, if the can is a little longer than necessary. The lever 154 can come 65 down to its extreme lower position without crushing the can. One end of the lever 154 is pivotally supported at 156 by means of a support 157 secured to the table top 1. The other end of the lever 154 is driven by reach rods 159. Each reach 70 rod 159 is connected to a cross rod 160, which, in turn, is pivotally connected to one end of a lever 162, see Fig. 12. The lever 162 is pivotally mounted at 163 upon a support 164. The other end of the lever 162 carries a cam follower 166 which 75 is engaged by a cam 167 non-rotatably mounted

upon the main drive shaft 41. Rotation of the cam 167 forces the pistons downwardly within the barrels at a faster rate than the barrels are moved downwardly.

The slides 105 of each barrel are withdrawn 5 laterally from the barrel to permit descent of the plunger and top as follows, see Figs. 20 and 21. The rolls 110 of the bell cranks 106 and 107 are moved downwardly upon descent of the pistons by engagement with cam surfaces 170 upon 10 the links 152. Further descent of the piston heads 150 forces the plunger a in the grease plunger barrel 67 into the container and forces the top b into the container that is disposed beneath the container topping barrel 68. The 15 piston head 150 in the container topping barrel 68 is flat while the piston head 150 in the plunger placing barrel has a projection 172 of sufficient length to press the plunger down in the can to its proper position.

Subsequently to positioning the plunger and top, the piston actuating cam 127 lifts the capping head to its elevated position. Simultaneously the triggers 104 are released so that the trigger heads rise in the magazines to a position 25 to block off descent of all of the plungers and tops in the magazines except the ones that are resting against the outside wall of the magazines. The triggers 104 during their upward movement 30 push the plungers and tops upward in the magazines.

At the time the capping head is being elevated the piston cam 167 releases the pistons which are thereupon elevated as follows: Each link 152 is connected to a chain 175, which passes over 35 a roll 176 and is connected to one arm of the bell crank 177, which is pivotally supported upon the central column 4. The other arm of the bell crank 177 is connected to a helical spring 178, which is attached also to the table top 1. Upon 40 release of the piston mechanism by cam 167 the spring 178 lifts the pistons. The slides 105 thus released are moved laterally into the barrels by means of helical springs 180.

By the construction described mechanism is 45 provided for the positive feeding of a grease plunger and a cover from magazines containing the same. The grease plunger and cover are fed mechanically to a mechanism for positively positioning them successively upon the open end of 50 a container.

Various changes may be made within the scope of the appended claims in which it is desired to claim all novelty inherent in the invention 55 as broadly as the prior art permits.

I claim:

1. In a container capping machine, a magazine for covers, the bottom wall of which is inclined at an angle to the vertical to a delivery opening at its lower end, a side wall of the magazine having a slot extending longitudinally of the magazine and an intermediate portion of which is inclined toward the bottom wall of the magazine, an arm extending into the slot and carrying a finger within the magazine, and means for actuating the arm longitudinally of the slot toward the lower end of the magazine whereby the finger is forced by the inclined portion toward the bottom wall of the magazine into engagement with a cover and longitudinally of the magazine to force 65 the cover through the delivery opening.

2. In a container capping machine, a magazine for grease plungers, the bottom wall of which is inclined at an angle to the vertical to a delivery opening at its lower end, a side wall of the maga- 75

- zine having a slot extending longitudinally of the magazine and an intermediate portion of which is inclined toward the bottom wall of the magazine; an arm extending into the slot and carrying a finger within the magazine, means for actuating the arm longitudinally of the slot toward the lower end of the magazine whereby the finger is forced by the inclined portion toward the bottom wall of the magazine into engagement with a plunger and longitudinally of the magazine to force the plunger through the delivery opening, a capping head, adjacent and in close proximity to the delivery end of said magazine including a tubular body portion having an inlet opening, and a discharge opening; and a transversely extending removable partition in the tubular body portion between the inlet and discharge openings; means for feeding a grease plunger from the magazine through the inlet opening into the tubular body portion; means for positioning a container substantially co-axial with said tubular body portion with its open end adjacent to the discharge opening thereof, means for telescoping the discharge end of the tubular body portion over the open end of the container, means for removing the partition from the body portion, and means for ejecting the plunger from the tubular body portion into said container.
3. In a container capping machine a magazine for grease plungers, the bottom wall of which is inclined at an angle to the vertical to a delivery opening at its lower end, a side wall of the magazine having a slot extending longitudinally of the magazine and an intermediate portion of which is inclined toward the bottom wall of the magazine; an arm extending into the slot and carrying a finger within the magazine; means for actuating the arm longitudinally of the slot between the lower end of the magazine whereby the finger is forced by the inclined portion toward the bottom wall of the magazine into engagement with a plunger and longitudinally of the magazine to force the plunger through the delivery opening, a capping head, adjacent and in close proximity to the delivery end of said magazine including a tubular body portion, having a discharge opening and with an inlet opening in its side wall through which the plunger is ejected from the magazine into the tubular body portion, a partition extending transversely of the tubular body portion to support the plunger, means for positioning a container substantially co-axial with said tubular body portion and with its open end adjacent to the discharge opening thereof, means for telescoping the discharge end of the tubular body portion over the open end of the container, and means for ejecting the plunger from the tubular body portion so as to be positioned within the open end of said container.
4. In a container capping machine, a magazine for grease plungers, the bottom wall of which is inclined at an angle to the vertical to a delivery opening at its lower end, a side wall of the magazine having a slot extending longitudinally of the magazine and an intermediate portion of which is inclined toward the bottom wall of the magazine; an arm extending into the slot and carrying a finger within the magazine; means for actuating the arm longitudinally of the slot toward the lower end of the magazine whereby the finger is forced by the inclined portion toward the bottom wall of the magazine into engagement with a plunger and longitudinally of

the magazine to force the plunger through the delivery opening; a capping head, adjacent said magazine, including a tubular body portion with an inlet opening in its side wall through which the plunger is ejected from the magazine into the tubular body portion, the body portion having a discharge opening, a partition extending transversely of the tubular body portion to support the plunger, means for positioning a container substantially co-axial with said body portion and with its open end adjacent the discharge opening thereof, means for effecting longitudinal movement of the tubular body portion whereby the delivery opening is closed by the side wall of the tubular body portion, and the discharge end is telescoped over the open end of the container, means for removing the partition from the body portion, a piston movable longitudinally of the tubular body portion to eject the portion through the discharge opening into the open end of said container, a latch for supporting the next to the bottom plunger within the magazine, and means associated with the capping head adapted to disengage the latch upon travel of the body portion transversely away from the magazine to permit the plungers to drop downwardly within the magazine.

5. In a container capping machine, a magazine for grease plungers, the bottom wall of which is inclined at an angle to the vertical to a delivery opening at its lower end; an arm having a finger extending into the magazine; means for actuating the arm toward the bottom wall of the magazine into engagement with a plunger and longitudinally of the magazine to force the plunger through the delivery opening; a capping head including a tubular body portion having an inlet opening and a discharge opening; a transversely extending removable partition in the tubular body portion between the inlet and discharge openings; means for positioning a container substantially co-axial with said body portion with its open end adjacent the discharge opening thereof, means for feeding a grease plunger from the magazine through the inlet opening into the tubular body portion; means for telescoping the discharge end of the tubular body portion over the open end of the container; and means for removing the partition from the body portion and for ejecting said plunger from the body portion into the open end of the container.

6. In a container capping machine, a magazine for grease plungers, the bottom wall of which is inclined at an angle to the vertical to a delivery opening at its lower end, a guideway having a guide surface extending longitudinally of the magazine, an intermediate portion of the guide surface being inclined toward the bottom wall of the magazine, an arm in slideable engagement with the guide surface and carrying a finger within the magazine, and means for actuating the arm longitudinally of the guide surface toward the lower end of the magazine whereby the finger is forced by the inclined portion toward the bottom wall of the magazine into engagement with a grease plunger and longitudinally of the magazine to force the grease plunger through the delivery opening.

7. In a container capping machine, a magazine for grease plungers, the bottom wall of which is inclined at an angle to the vertical to a delivery opening at its lower end, a guideway having a guide surface, an intermediate portion of the guideway being inclined toward the bottom wall of the magazine, an arm in slideable contact

with the guide surface and carrying a finger within the magazine, means for actuating the arm longitudinally along the guideway toward the lower end of the magazine whereby the finger is forced by the inclined portion toward the bottom wall of the magazine into engagement with a grease plunger and longitudinally of the magazine to force the grease plunger through the delivery opening, and means for snapping the finger into its elevated position at the end of its downward stroke.

8. A machine for positioned application to the open end of a container, of a series of closure elements of which series each element is separately applied in sequence comprising, a series of magazines for the respective closure elements each of said magazines having a downwardly inclined bottom wall and a discharge end, said magazines being disposed in spaced relation to each other

and to a conveyor means for containers; a tubular capping head associated with each magazine and with said conveyor means, having an inlet opening adjacent the discharge end of the magazine and a discharge opening adjacent said conveyor means, and transverse removable partitions disposed within the head between said openings; a means for positioning each container, substantially co-axial with each capping head in the series of magazines and heads, with its open end adjacent the discharge opening of each head in the sequence; means for discharging single elements from the magazine into the capping head; means for telescoping said head over the open end of the container adjacent thereto; and means for removing the partitions in said head and for ejecting the elements therein into said container.

RICHARD D. ANDERSON.
